CLAIM

The ornamental design for a ice scraper, as shown and described.

DESCRIPTION

FIG. 1 is a perspective front view of the ice scraper; FIG. 2 is a first side view of the ice scraper of FIG. 1; FIG. 3 is a top view of the ice scraper of FIG. 1; FIG. 4 is a front view of the ice scraper of FIG. 1; FIG. 5 is a rear view of the ice scraper of FIG. 1; FIG. 6 is a bottom view of the ice scraper of FIG. 1; and, FIG. 7 is a second side view of the ice scraper of FIG. 1. The dot-dash broken lines immediately adjacent the shaded areas represent the bounds of the claimed design, while all other broken lines are included for the purpose of illustrating portions of the ice scraper; the broken lines form no part of the claimed design.
